METHOD OF MAKING PIEZOELECTRIC CRYSTAL STRUCTURES

Hal F. Fruth, Chicago, Ill., assignor to Galvin Manufacturing Corporation, Chicago, Ill., a corporation of Illinois

Application July 3, 1943, Serial No. 493,419

5 Claims. (Cl. 171—327)

The present invention relates to methods of making piezoelectric crystal structures and more particularly to improved methods of forming conductive electrode surfaces upon the faces of piezoelectric crystals.

One of the problems involved in the manufacture and use of piezoelectric crystals is that of providing a satisfactory electrode structure by means of which operating potentials may be applied across the crystal faces. Many different types of crystal holders having an equal number of different electrode structures have been devised in an attempt to meet this problem. Also, various methods have been developed for bonding a suitable conducting material upon the crystal faces in order to produce integral conductive electrodes to which circuit connections may be made. When the electrodes are formed by the latter methods, however, difficulties are experienced in preparing the crystal surfaces for metallizing, coating the crystal faces to the depth required to obtain the desired resonant frequency characteristic, and preventing the formation of electrical and mechanical metallic connections between the metallized faces of each crystal incident to the metallizing operation. Moreover, all such methods require a considerable amount of handling of the crystals and a considerable number of individual operations on each crystal, with the result that the crystals are frequently broken and the further result that a considerable amount of labor is involved in the production of the metallized faces on each crystal.

It is an object of the present invention, therefore, to provide improved methods for metallizing the faces of the piezoelectric crystal in order to impart a predetermined resonant frequency characteristic thereto and to provide electrically and mechanically separated metallic electrode surfaces upon the faces thereof.

It is another object of the invention to substantially eliminate all precision steps in metallizing the faces of a piezoelectric crystal to provide electrodes thereon.

It is a further object of the invention to provide an improved method of metallizing the faces of piezoelectric crystals, which may be employed to produce structures having uniform resonant frequency characteristics closely conforming to a desired predetermined frequency standard.

According to still another object of the invention, the improved method may be easily practiced without individual handling of the crystals to insure opening of all metallic bonds between the metallized faces of each crystal.

In accordance with still another object of the invention, all steps of the improved method may be practiced with but a minimum number of individual operations on each crystal, with a corresponding decrease in the likelihood of crystal breakage, an increase in the speed of production, and a material saving in the amount of labor involved in metallizing the faces of each crystal.

The invention, both as to its organization and 10 method of operation, together with further objects and advantages thereof, will best be understood by reference to the following specification taken in connection with the accompanying drawings, in which:

15 Fig. 1 is a side sectional view of improved tumbling apparatus which may be utilized in practicing certain steps of the improved method;

Fig. 2 is a side view of improved apparatus which may be utilized to practice another step 20 in the improved method;

Fig. 3 is an end sectional view of the apparatus shown in Fig. 2;

Fig. 4 is a fragmentary sectional view illustrating the disposition of metallized crystals with 25 in one of the grinding tubes embodied in the apparatus shown in Fig. 1; and

Fig. 5 is an end sectional view of the grinding tube shown in Fig. 4.

Before considering the apparatus illustrated in 30 the drawings, it may be pointed out that the resonant frequency characteristic of a piezoelectric crystal formed of quartz, for example, is primarily determined by the thickness and mass of the crystal. It may be pointed out further 35 that to produce a crystal having a desired resonant frequency characteristic, it is the usual practice to slice a crystal blank from a bar of crystal stock, following which the blank is rough ground on an abrasive wheel or the like to the approximate desired dimensions. Thereafter the blank 40 is edge ground to remove irregularities from the edges thereof and is face ground to reduce the thickness and mass thereof until the crystal is characterized by the desired resonant frequency 45 characteristic.

In accordance with the present invention, a batch of crystals which are to have the same resonant frequency characteristics and are to be provided with metallized electrode faces are, following the initial cutting and rough grinding operations, subjected to an additional controlled random grinding operation by means of which scratches and other surface irregularities are removed from the crystals, and the thickness and 50 mass of each crystal are reduced sufficiently to

raise the resonant frequency of each crystal to a value well above the desired resonant frequency. After the random grinding step is completed all surfaces of each crystal are built up by metalizing the same, whereby the mass and thickness of each crystal structure is sufficiently increased to lower the measured resonant frequency of each crystal to a value which either equals or is lower than the desired value. Following the surface metalizing operation, the crystals as a batch are subjected to a controlled random edge grinding step by means of which the metallic bonds between the metalized face surfaces of each crystal are completely severed, thereby electrically and mechanically to isolate the metalized electrode surfaces of each crystal one from the other. Also during the random edge grinding operation, the edges of each crystal structure are beveled or chamfered in order to remove therefrom any irregularities or discontinuities which might tend to produce spurious oscillation of the crystal when subjected to use under certain temperature conditions. After the random edge grinding operation is completed, the crystals are measured as to the resonant frequencies thereof and are grouped or classified in accordance with their resonant frequencies. Those crystals having resonant frequencies which closely approximate the desired resonant frequency may require no further treatment. On the other hand, the crystals having resonant frequencies lower than the desired resonant frequency are, as groups, subjected to random finish grinding operations on a controlled time basis such that the resonant frequencies of the crystals in each class or group are accurately raised to the desired value.

The novel method, as briefly described above and referred to with greater particularity in the following explanation, may conveniently be practiced by utilizing apparatus of the character illustrated in the drawings. More specifically, the tumbling apparatus, as shown in Fig. 1, is well adapted for use in initially grinding the crystal blanks to raise the resonant frequencies thereof above the particular desired resonant frequency. It is also well adapted for use in finish grinding the metalized faces of those crystals which, following the edge grinding operation, are found to possess resonant frequencies below the desired value. The apparatus illustrated in Figs. 2 to 5, inclusive, of the drawings, on the other hand, is well suited for use in edge grinding the metalized crystals, for the purpose of opening the bonds between the metalized face surfaces of each crystal after the metalizing step is completed.

Briefly considered, the random grinding apparatus, as shown in Fig. 1 of the drawings, comprises a base 10 having a carriage or housing 11 tiltably mounted thereon by means of hinges 12, which are secured to the base 10 and to the lower edge of the rear wall 11a of the carriage 11. The carriage 11 houses driving means 13 which includes a motor supporting member 14, a rotatable shaft 15, and a speed reducing gear train connecting the drive shaft of the motor and the shaft 15. The shaft 15 functions to support and rotate a tumbler cup 16 which is located exteriorly of the carriage 11. The cup 16 is of square cross section along the body thereof and has a round neck 16a suitably threaded at the end to receive an internally threaded cover 22. More specifically, the shaft 15 is journaled in bearing plates 17a and 17b suitably secured to

the rear and front walls 11a and 11b, respectively, of the carriage 11. Suitable collars 18a and 18b, which may be slipped over the shaft and set in a given position by means of set screws or the like, are provided adjacent the bearing plates 17a and 17b, respectively, in order to limit axial movement of the shaft 15. A cup supporting plate 19 is rigidly mounted upon the right end of the shaft 15 and carries four outwardly projecting, angularly spaced apart resilient arms 20, which, in combination, define a nest for receiving the cup 16. The four arms 20 may be bent over from an annular base 21, so that a one-piece construction is provided, and the annular base 21 may be suitably secured to the outer surface of the plate 19 by spot welding the inner edge thereof to the adjacent plate surface. With the tumbler cup 16 nested within the resilient arms 20, the bent over end portions 20a of the arms 20 engage the base of the neck 16a to hold the cup 16 in place. If desired, a rubber band 21a may be used to increase the pressure of the arms 20 against the side walls of the cup 16.

For the purpose of imparting rotary movement to the shaft 15, thereby to rotate the tumbler cup 16, a motor 24 supported upon the member 14 is provided. This motor is arranged to drive the shaft 15 through a speed reducing gear train which comprises the gears 25, 26, 27 and 28. The two intermediate gears 26 and 27 of the train are mounted for rotation with a shaft 29 which is suitably journaled at its ends in the side walls of the member 14. It will be understood in this regard, that the gear 25 which meshes with the driven gear 28 is rigidly mounted upon the end of the motor shaft, and that the driven gear 28 is rigidly mounted upon the tumbler drive shaft 15. Cap screws or bolts 30 extending through holes drilled in the side walls 11a and 11b of the carriage 11 and threaded into the side walls of the member 14 may be utilized for supporting the motor 24 and the speed reducing gear train within the carriage 11.

In order to adjustably tilt the carriage 11 with reference to a horizontal surface upon which the base 10 is supported, thereby to change the angle of inclination of the tumbler cup 16 with reference to the horizontal, adjusting means comprising a link 31 and a wing nut assembly 32 is provided. More specifically, the lower end of the link 31 is pivotally connected to an edge surface of the base 10 by means of a pivot screw 33, and is provided with a slot 34 in which the bolt 32a of the wing nut assembly 32 is slidably disposed. The base of the bolt 32a is pivotally anchored upon a lug 32c which is suitably secured to the outer face of the carriage wall 11b. With this construction, the wing nut 32b may be loosened in order that the carriage 11 and the parts supported thereby may be tilted to any desired angular position, and then tightened to retain the carriage 11 and the tumbler cup 16 in the selected position.

Although the motor 24 may be of any desired adjustable speed type, it is preferably an adjustable speed direct current motor, and may be connected for energization from a direct current source connected to the terminals 35. An adjustable rheostat 36 is provided in one side of the circuit for energizing the motor 24 in order that the speed of operation of the motor may be varied as desired.

In utilizing the above described apparatus to practice the present improved methods, piezoelectric quartz crystal blanks which have been

cut from the crystal stock and then machine ground to rectangular dimensions slightly larger than those desired are mixed with a charge of abrasive material in the tumbler cup 16, and the cup with the cover 22 fitted over the open end thereof is inserted between the arms 20. Operation of the motor 24 to rotate the tumbler cup at the speed established by the setting of the rheostat 36a is now initiated. During rotation of the tumbler cup, random relative movement occurs between the crystals and the abrasive material so that all surfaces of the crystals are ground or abraded. The extent of the grinding action per unit time interval is of course determined by the speed of the tumbling action as established by the speed of rotation of the cup 16, and by the character and fineness of the abrasive material used.

More specifically considered, the preparation of a given batch of quartz crystals for metalizing may be accomplished by grinding the selected crystals of the batch at a relatively high grinding speed until the resonant frequencies thereof are well above the particular resonant frequency desired for each crystal. In this regard it will be understood that the crystal blanks as initially cut from the crystal stock are of such dimensions that the resonant frequency of each crystal is well below the particular resonant frequency which is desired. During the preparatory grinding step, therefore, a considerable amount of grinding may be required in order to bring the resonant frequencies of the respective crystals to the desired high values. For this preliminary grinding step, a grinding media may be employed which comprises grains of gravel or fused alundum having granules of boron carbide or silicon carbide coated upon the surfaces thereof by a suitable vitrification process or by coating the gravel or alundum grains with an air setting sodium silicate mixture containing the particles of boron carbide or silicon carbide.

After the crystal blanks have been mixed with the abrasive material within the tumbling cup 16, the mixture is tumbled for a predetermined time interval at a preestablished tumbling rate. As the tumbling of the mixture proceeds, the crystals are wholly free to move at random through the abrasive material, contact at all times being maintained between two or more surfaces of each crystal and a relatively large number of abrasive granules. Stratification of the crystals in certain zones of the mixture is completely avoided, with the result that the extent of random movement of the many crystals is approximately the same. Accordingly, the crystals are ground at substantially the same rate. In fact, using a grinding material of the character described above, it has been found that the resonant frequencies of the crystals may be changed at a substantially uniform rate of approximately 700 cycles per hour when the tumbling cup 16 of the apparatus in use is rotated about a horizontal axis at a speed of 26 revolutions per minute. If, therefore, the approximate resonant frequencies of the unfinished crystals are known, and the particular frequency to which each crystal is to be ground is also known, the time interval during which the mixture is tumbled during the preparatory grinding step may be so chosen that the resonant frequencies of all crystals in the batch are raised to values well above the desired frequency.

As outlined above, after the preparatory grinding operation is completed, the crystals are sepa-

gated from the mixture, are cleaned, and are subjected to a metallizing step whereby all surfaces of each crystal are coated with metal to a desired depth. More specifically, the metallizing of the crystal surfaces may be effected by a sputtering process utilizing gold, silver or other precious metals, which is carried out in such a manner that particles of the particular metal in use are bonded to and form a coating of suitable depth over all surfaces of each crystal. Alternatively, a combination spraying and plating process may be employed. In practicing the latter method, gold, for example, is first sprayed upon the crystal surfaces and particularly the faces thereof, in an entirely indiscriminate manner, following which the gold film is plated with gold to build up the metallic coating to the desired thickness. In this regard it will be understood that no care need be exercised in preventing the metal from being deposited upon the side surfaces of the crystals. Moreover, the amount of metal which is deposited upon the surfaces of each crystal requires no accurate control, other than that which is necessary to insure that the coating will be of sufficient depth to decrease the frequency of the composite structure below the desired resonant frequency.

After the surface metallizing step has been completed by utilizing one of the methods described above, the metallized crystals are subjected to the edge grinding operation for the purpose of completely severing any metallic bond which may have been formed between the metallized faces of each crystal, and for the additional purpose of beveling or chamfering the edges of each structure to remove irregularities therefrom. The edge grinding may easily be effected on a controlled basis by utilizing the apparatus shown in Figs. 2 to 5, inclusive, of the drawings. Briefly considered, this apparatus comprises a base 110 having a U-shaped carriage 111 tiltably mounted thereon within two upstanding bracket pieces 112 and 113. Side members 114 and 115 which are flanged at the ends thereof to overlie the end panels 111a and 111b of the carriage 111 are provided for rotatably supporting the carriage upon the two bracket pieces 112 and 113. More specifically, the flanged portions of the two side members 114 and 115 are riveted to the carriage panels 111a and 111b adjacent the tops thereof and carry pivot pins 116 and 117 at aligned central points thereof, which are suitably journaled in bearing members respectively carried by the two bracket pieces 112 and 113. The carriage 111 is arranged detachably to support a grinding tube assembly 8 which comprises six grinding tubes 118 of the same length and internal diameter. These tubes are arranged with their long axes in parallel and offset from the center of rotation of the tubes. They may be formed of glass, metal or any other material having the required hardness to resist abrasion. Rollers 119 and 120 are utilized to rotatably support the tubes 118 upon the carriage 111. To this end, six equiangularly spaced-apart and aligned openings are cut through the two rollers 119 and 120 for receiving the six tubes. For the purpose of rotatably supporting the rollers 119 and 120 upon the carriage 111, two driving rollers 121a and 121b rigidly mounted upon a shaft 122 at opposite ends of the carriage 111, and two idler rollers 123 mounted upon a shaft 124 at opposite ends of the carriage 111, are employed. The two shafts 122 and 123 are suitably journaled in the top corner portions of the carriage end panels 111a and 111b.

A driving motor 125, which is mounted upon the floor 111c of the carriage 111, is provided for imparting rotary movement to the rollers 118 and 120, thereby to rotate the grinding tubes 118 about the longitudinally aligned centers of the two rollers. This motor is equipped with a motor pulley 126 which is connected by a driving belt 127 to drive a second pulley 128 rigidly mounted upon the roller drive shaft 122. In order to continuously tilt the carriage 111 between two extreme positions, wherein the grinding tubes 118 are oppositely inclined with respect to the horizontal, a second motor 129 is provided, which is crank connected to the end panel 111b of the carriage. More specifically, the rotor shaft of this motor carries a wheel 130 having an eccentric pin 131 mounted thereon which is journaled within one end of a crank arm 132. The opposite end of the arm 132 is pivotally connected to the carriage end panel 111b by axis means comprising the two bearing brackets 133 and 134 and a pivot pin 135. As thus arranged, rotary movement of the wheel 130 serves continuously to reciprocate the carriage 111 between two extreme positions wherein the grinding tubes 118 respectively occupy the positions shown in full lines and in dash lines in Fig. 2 of the drawings.

As indicated above, the tubes 118 are mounted within the openings provided in the two rollers 118 and 120. To this end, the rollers may be provided with tube receiving openings having diameters slightly greater than the tube diameters, so that rubber grommets 136 may be inserted within the roller openings. The tubes 118 may then be inserted through the aligned grommet openings of the two rollers so that a semi-rigid assembly is provided which is completely removable from the supporting rollers 121 and 123. It will be noted that the upper inner edge portions of the two carriage end panels 111a and 111b serve as friction bearing surfaces against which the side surfaces of the rollers 118 and 120 may bear to prevent movement of the grinding tube assembly 9 in a direction longitudinal of the grinding tubes. In other words, with the tube assembly positioned upon the rollers 121 and 123 of the carriage, the engagement of the rollers 118 and 120 with the upper inner edge portions of the end panels 111a and 111b serves to prevent the tube assembly from sliding off of the carriage.

In utilizing the above-described apparatus for the purpose of grinding the edges of the metallized piezoelectric crystals, the crystals are disposed within the tubes 118. For the purpose of retaining the crystals within the tubes, each tube is provided at each end thereof with a rubber stopper 137 which may be readily removed for the purpose of inserting or withdrawing crystals from the tube chamber. In order to produce random changes in the position of each crystal relative to the tube within which it is confined, a baffle or obstruction 138 is provided at one or more points each along each tube. Each baffle may comprise a small narrow strip of adhesive tape extending longitudinally of the tube in the manner shown in Figs. 4 and 5 of the drawings. Depending upon the type of random movement of the crystals which is desired, the baffle strips may be positioned at different points intermediate the ends of each tube or may be provided at the ends of each tube.

In the operation of the apparatus shown in Figs. 2, 3, 4 and 5 of the drawings, each of the tubes 118 is loaded with a charge of metallized crystals and abrasive material in the manner

more fully explained below, after which the stoppers 137 are inserted in the open ends of the tubes for the purpose of confining the abrasive material and crystals therewithin. This operation may be performed by removing the grinding tube assembly 9 from the carriage and holding the same in any angular position which is convenient for loading the individual tubes with a charge of the metal crystals and abrasive material. The grinding tube assembly is then positioned upon the carriage with the rollers 118 and 120 in engagement with the driving rollers 121 and the idler rollers 123. The motors 125 and 129 are now energized for the purpose of simultaneously rotating the tubes 118 and tilting these tubes back and forth so that the angle of inclination of the tubes with respect to the horizontal is continuously changed. As the tube assembly 9 is tilted, each crystal within each tube is slid longitudinally from one end of the enclosing tube to the other. The rotary movement of the tubes causes each crystal to slide over the inner surface of the enclosing tube in a substantially circular path. As a result of the combined movements of each crystal through its enclosing tube, the path followed by any selected point on any selected crystal during movement of the crystal from one end of the enclosing tube to the other is in the form of a helix. The manner in which the positions of the crystals with respect to their respective enclosing tubes are changed at random and the edge grinding operations are carried out, is fully explained below.

As will be apparent from the foregoing explanation, each metallized crystal structure is of substantially rectangular pattern having a length which is somewhat greater than its width. These dimensions are taken into account in determining the inner diameters of the tubes 118 which are utilized in the edge grinding apparatus. Preferably, the dimensions of the metallized crystals as related to the tube diameter are about as indicated in Fig. 5 of the drawings. As there shown, the diameter of the illustrated tube 118 is so chosen that when a metallized crystal is supported at its edges with its axis extending longitudinally of the tube, a second crystal may be supported thereabove with the long axis thereof extending transversely of the tube and with the adjacent surfaces of the two superimposed crystals in spaced-apart relation. With this arrangement, the upper crystal is prevented from increasing the contact pressure between the inner surface of the tube and the engaging edges of the lower crystal, and the presence of the lower crystal beneath the upper crystal is prevented from reducing the contact pressure between the inner surface of the tube and the engaging edges of the upper crystal.

As indicated above, to condition the disclosed edge grinding apparatus for grinding the metallized edges of the crystals, the tubes 118 are each loaded with a portion of the crystal batch and a charge of abrasive material. The abrasive material may comprise a small amount of diamond powder or boron carbide, for example, the particular grinding speed being determined to a large extent by the size of the grinding particles employed. Thus, if rapid grinding is desired, diamond powder of from No. 110 to No. 150 screen mesh may be used. On the other hand, if less rapid grinding and a higher polish of the chamfered surfaces are to be obtained, No. 320 to No. 400 screen mesh grinding material may be utilized. The amount of grinding material used in

each tube will of course depend upon the dimensions of the tube. For example, when tubes having a length of about 60 inches and an internal diameter of 1.0625 inches are employed, satisfactory grinding is obtained if approximately two carats of from No. 100 to No. 150 screen mesh diamond powder is used in each tube. On the other hand, if the final grinding powder of from No. 320 to No. 400 screen mesh is employed, approximately two to three carats of the grinding material should be used in each tube.

After each tube is loaded with a batch of metalized crystals and a charge of abrasive material and the tubes 118 are suitably positioned upon the carriage 111, operation of the driving motors 125 and 130 may be initiated for the purpose of starting the grinding operation. Due to the continuous and reverse tilting movement of the tubes 118, each metalized crystal within each tube is slid longitudinally of the tube over the inner abrasively coated surface thereof. Concurrently therewith, and due to the rotation of the tube assembly 8 by the motor 125, the tubes are rotated about the axial centers of the rollers 119 and 120, so that the inner surface of each tube is slid beneath the edge surfaces of each crystal which it houses. After rotation and reciprocation of the tube assembly is started, the crystals tend to align themselves along the lengths of their respective enclosing tubes with only the straight edge sections thereof bearing against the inner surfaces of their enclosing tubes. The abrasive material is of course soon spread over the inner surface of each tube to produce an abrasive surface against which the metalized edge portions of the crystals bear. Also, the contact pressure at the points of engagement of the edges of a particular crystal with the abrasively coated inner surface of its enclosing tube is primarily determined by the weight of the crystal. This is due to the fact that the longitudinal movement of the crystals through the tubes tends to prevent the crystals from becoming stacked one above the other. Due to the abrasive action of the abrasive material, the metal at the edges of each crystal is soon cut away as the crystals are slid over the surfaces of their enclosing tubes. As the abrading action continues, the edges of each crystal are also cut away to widen the gaps between the metalized side and face surfaces of the crystal and to remove any high points which may be present in the crystal edges. In this connection it is pointed out that the movement of the crystal edges longitudinally of the tubes prevents transverse scratches from being produced in the chamfered crystal surfaces which are soon formed at the edges of each crystal between the metalized side and face surfaces thereof. Similarly, the sliding of the crystal edges circumferentially of the abrasive surfaces against which they bear prevents the chamfered surfaces from being scratched longitudinally, incident to the sliding of the crystals back and forth within their enclosing tubes.

Preferably, the speed at which the tilting motor 129 is operated is so related to the lengths of the tubes 118 and the angle of inclination of the tube assembly with respect to the horizontal that a metalized crystal disposed at the elevated end of a tube will just slide to the other end of the tube before the angle of inclination of the tube is reversed. It has been found that if tubes fifty-eight inches long are employed and the maximum angle of inclination with respect to the hori-

zontal is five degrees and forty-two minutes, a crystal will be slid from one end of an enclosing tube to the other if the tilting motor 129 is operated at a speed of one revolution per minute. 5 The grinding tubes are rotated at a much faster speed, a speed of from eight to ninety revolutions per minute having been found to be satisfactory in practice. It will be understood, therefore, that the maximum abrading action is produced by rotation of the tubes to slide the abrasively coated inner surfaces thereof beneath the edges of the crystals which are supported upon these surfaces. However, the longitudinal movement of the crystals prevents the transverse scratches from being produced in the chamfered edge surfaces during the rapid rotation of the abrading surfaces.

The longitudinal movement of the metalized crystals along the tubes is also utilized to change the positions of the crystals within the tubes so that different metallically coated edge sections thereof are brought to bear against the abrasively coated inner surfaces of the tubes. To consider one aspect of the crystal tumbling movement, it may be assumed that the uppermost crystal as shown in Fig. 5 of the drawings is slid into a position where it is transversely aligned with the baffle strip 138. As the illustrated tube 118 in which this crystal is disposed is rotated, one edge of the strip 138 engages one side of the crystal 20 so that during continued rotation of the tube the crystal is turned over to reverse the edges thereof which bear against the abrasively coated inner surface of the tube. The reversal in the position of the crystal within the tube may occur several 25 times during the period when the crystal is disposed in transverse alignment with the strip 138. During this period the crystal is not only turned over so that alternate faces thereof face downwardly, but in addition is turned end for end so that all eight of the metallically coated edges thereof are at one time or another brought to bear against the abrasively coated inner surface of the tube. Incident to the turning of the crystal end for end, the metallically coated corner edges thereof are also subjected to the action of the abrasive material so that they too become smoothly rounded. The particular set of oppositely disposed edges which may remain in contact with the abrasively coated surface of the 30 tube during the longitudinal sliding movement of the crystal through the tube depends upon the particular position at which the crystal is brought to rest after it is moved out of transverse alignment with the baffle strip 138.

55 From the above explanation, it will be understood that the edge grinding of the metalized crystals disposed within the tubes 118 is produced with a completely random action; that is, the back and forth movement of the crystals with respect to the abrasive surfaces does not follow any predetermined or ascertainable pattern but differs for each crystal. On an average basis, however, it has been found that all eight edges and eight corners of each crystal are, in a given time interval, chamfered or ground to almost precisely the same extent. This time interval is of sufficient length to insure that a substantial gap will be produced between the metallic side and face surfaces at all points around the edges of the crystal. Since the abrading action is accomplished in a wholly random manner and at exceedingly low contact pressures between the engaged edge surfaces of the crystals and the abrading surfaces, the surfaces of the chamfer-

produced on the edges of the crystals are almost entirely free of scratches or other irregularities and are highly polished.

As previously indicated, after the edge grinding operation is completed, the crystals are segregated from the grinding material, are classified according to the resonant frequencies thereof, and those crystals which have frequencies below the desired value are subjected to a finish grinding step in order to raise the frequencies thereof to the desired value. Apparatus of the character shown in Fig. 1 of the drawings may be employed for the final finish grinding operation of those metalized crystals having frequencies which are too low. Preferably, the finish grinding step should not proceed at a too rapid rate and should be carried out on a controlled time basis. To this end, the crystals of the respective frequency groups are separately mixed with different charges of abrasive material. It has been found that No. 220 screen mesh silicon carbide is entirely satisfactory for the finish grinding step and will not produce sufficiently rapid abrasion of the metalized crystal surfaces to prevent accurate control of the frequency change on a calibrated time basis. The separate mixes of crystals and abrasive material are made in the different tumbler cups of several tumbling mills of the character shown in Fig. 1 of the drawings, and each mix is separately tumbled or agitated at a predetermined tumbling rate for a particular time interval which is dependent upon the difference between the average resonant frequency of the particular class or group of metalized crystals and the desired resonant frequency. Assuming, for example, that there are three different classes or groups of metalized crystals which respectively contain crystal structures of different resonant frequencies, and also that the same tumbling speed is used for the different mixes, three different intervals of tumbling time are required for the three different mixes. As the final grinding steps are completed for the crystals of the different groups, the crystals may be removed from the grinding mix, cleaned, and checked for frequency, following which they are ready for use.

While one embodiment of the invention has been disclosed, it will be understood that various modifications may be made therein, which are within the true spirit and scope of the invention.

I claim:

1. The method of forming electrode surfaces upon the faces of a piezoelectric crystal, which comprises metalizing substantially all surfaces of said crystal, supporting the metalized crystal at its edges upon an abrasive trough-like surface, and producing relative movement between said crystal and said surface in order to open the metallic connection between the metalized face surfaces of said crystal.

2. The method of forming electrode surfaces upon the faces of piezoelectric crystals, which comprises metalizing substantially all surfaces of each crystal, supporting the crystals upon an abrasive surface with only the metalized edge portions thereof bearing against said surface, producing

relative sliding movement between said abrasive surface and the metalized edges of said crystals, thereby to open the metallic connection between the metalized faces of each crystal at the edges thereof which bear against said abrasive surface, and utilizing the relative movement between said surface and the crystals to change at random the metalized edge portions of the crystals which bear against said surface, thereby to insure complete severance of the metallic connection between the metalized face surfaces of each crystal.

3. The method of forming electrode surfaces upon the faces of piezoelectric crystals, which comprises metalizing substantially all surfaces of each crystal, supporting the crystals upon an abrasive surface with only the metalized edge portions thereof bearing against said surface, producing relative sliding movement between said abrasive surface and the metalized edges of said crystals, thereby to open the metallic connection between the metalized faces of each crystal at the edges thereof which bear against said abrasive surface, utilizing the relative movement between said abrasive surface and the crystals to change at random the metalized edge portions of the crystals which bear against said surface, thereby to insure complete severance of the metallic connection between the metalized face surfaces of each crystal, and agitating the metalized crystals in the presence of a charge of loose granular abrasive material, thereby to reduce the thickness of the metal at each crystal face.

4. The method of grinding the faces of a piezoelectric crystal having faces and having a metalized coating on substantially all surfaces, such grinding to provide a two-electrode crystal with desired frequency characteristics, which comprises supporting the crystal on abrasive material within a container, rotating the container at such a speed that relative movement between the abrasive material and the crystal is accomplished to grind the face portions of the metalized crystal to remove metal therefrom, and utilizing the relative movement between the abrasive material and the crystal to change at random the metalized outside portions being ground.

5. The method of grinding a piezoelectric crystal having faces and having a metalized coating on substantially all surfaces, which comprises grinding the metal on the edge surfaces to mechanically and electrically disconnect the metalized face surfaces of the crystal, mixing the crystal with loose abrasive material within a container to provide a mixture of crystal and abrasive material therein, agitating the mixture at such a speed that relative movement between the abrasive and the crystal is accomplished to grind metal from the metalized face surfaces and produce a change in the frequency characteristic of the crystal thereby, and utilizing the relative movement of the loose abrasive material and the crystal to upset the crystal in a manner such that both faces are ground during the entire operation.
